JOHN W. HERKEL, OF MIDDLEVILLE, AND JAMES D. MCCOY, OF LITTLE FALLS, NEW YORK.

GUARD FOR LEATHER-PRESSING MACHINES.

Application filed December 1, 1922. Serial No. 604,223.

Our invention relates to a guard for a leather pressing machine and we declare the following to be a full, clear, concise and exact description thereof sufficient to enable anyone skilled in the art to which it appertains to make and use the same, reference being had to the accompanying drawings in which like reference characters refer to like parts throughout the specification.

10 The object of the invention is to provide a guard for a leather pressing machine that will be positive in action, whereby to not only warn the operator of approaching danger, but also to prevent the operator 15 from inserting his hands within the danger zone when the machine is in operation. The benefit of such a guard will be apparent in view of the fact that persons operating leather pressing machines oftentimes attempt, at the last moment, to smooth out the leather placed on the vertically movable table thereof even after the machine has been placed in operation and the table begun to move upward with fatal results to their 20 hands. The invention is designed, therefore, to prevent such fatal injuries and will be understood by referring to the drawings in which:

Fig. 1 is a perspective view of a leather 30 pressing machine showing the guard mechanism attached thereto;

Fig. 2 is a side elevation of the leather pressing machine, showing the guard mechanism attached, parts of the machine being 35 in fragment;

Fig. 3 is an enlarged detail view, showing a side elevation of the clutch mechanism employed;

Fig. 4 is a detail view, showing a perspective of the guard mechanism separated from the leather pressing machine.

Fig. 5 is an enlarged detail view, showing a perspective of an adjustable turn buckle employed;

Fig. 6 is an enlarged detail view of a friction stop employed.

Fig. 7 is a detail perspective view somewhat enlarged of a mutilated cam employed.

Fig. 8 is a sectional detail view of the upper end of a curved forked member employed and co-operating connecting plate.

Fig. 9 is a detail enlarged view showing a perspective of a spring used.

Referring more particularly to the drawings, a leather pressing machine of well

known construction is represented by 1. Said machine has a vertically movable table 2 and a stationary presser overhead 3. The movable guard 4, which is attached to said machine is novel and embodies four side 60 members 5 fastened together in any suitable manner. Said sides 5 are made preferably of heavy card board or stiff fabric, whereby to yield sufficiently to allow for the withdrawal of the hand of the operator or other 65 object therewithin and under conditions to be hereinafter stated.

The mechanism for actuating guard 4 is the same on each side of the machine. Two of the opposite sides 5 are extended on opposite ends at 10, 10 to which are attached the opposite adjustable ends 11 of the curved forked members 12, 12. Teeth 11^a are formed on the upper edge of members 12, 12, in each instance, whereby to engage the 70 counter teeth 11^a formed in plate 11^b bolted to the side 5. A bolt 11^c projects through an enlarged recess 11^e formed in the upper edge of member 12 and through a corresponding recess in plate 11^b, whereby to 75 hold the parts in given adjusted position. The other ends of members 12, 12 are secured, in each instance, in suitable recesses in an adjustable housing member 13 by means of set screws 12^a. Member 13 is 80 equipped with a central recess for the projection therethrough of the vertically movable rod 15 to which member it is held by bolts 16, 16. Rod 15 is adapted to slide in guide recesses formed in bracket 17 attached 85 to the side edge of the movable table 2.

Rod 15 carries a pin 20 adapted to strike pawl 21 fulcrumed at 22 to bracket 23 attached to the frame of machine 1. Bracket 23 has a projecting member 23^a through 90 which rod 15 is guided. Pawl 21 is free to turn on its fulcrum 22. One end thereof, as at 24, is made heavier than the other, whereby said end will be normally lowermost under the attraction of gravity. 100 Moreover, spring 27 is employed and attached to end 24 at one end and to keeper 58 at the other to insure the normal position of said pawl 21, whereby its under edge 25 will engage recess 26 made in horizontal 105 sliding bar 30. Bar 30 is carried in guide recesses in laterally projecting arms 31, 31 made on bracket 23 which is attached to the wall of the machine. Bar 30 is pivoted to member 33. Member 33 is connected to 110

member 34 by a screw bolt 34^a. Member 34 is attached to lever 35 by a rod 35^a that is pivoted at one end to said lever 35. Members 33 and 34 together with bolt 34^a form a turnbuckle, whereby to adjust the length of bar 30 to time the actuation of pawl 21 correctly.

Lever 35 is fulcrumed at 36 to the end of rock shaft 37. The lower end of lever 35 is united by a link 38 to slide rod 39 and by a link 40 to the lower end of auxiliary lever 41. Auxiliary lever 41 is fulcrumed adjacent its center portion upon a shaft 42 projecting laterally from bracket 43 fixed to the frame of the machine.

The upper end of auxiliary lever 41 has several apertures 45 for connecting the adjustable end of link 46 which is pivoted also at the opposite end to the lower part of a pawl or finger 47. Pawl 47 has a pin 48 projecting laterally therefrom, which pin 48 will protrude laterally into the path and come to rest normally against the upper edge of link 46, as shown in dotted lines in Fig. 2. A spring 50 that is attached at one end to a pin fastened to pawl 47 and at the other to link 46, as shown in dotted lines in Fig. 2, has its middle part coiled about the fulcrum of pawl 47, is adapted to draw the upper end 49 of pawl 47 towards the upper edge of link 46, as shown in dotted lines in Fig. 2. Another arm 51 is pivoted also at one end to the lower part of link 46 and at its opposite end to depending member 52 of bracket 43. Pawl 47 and arm 51 form a toggle joint, whereby to pass over center and thereby stabilize the relative vertical position of pawl 47 and arm 51 when in full line position, as illustrated in Fig. 2. In this full line position of pawl 47 and arm 51 the upper end 49 of pawl 47 will rest against the shoulder formed at 53 in vertically movable rod 15 and, thereby, hold said rod 15 in elevated position, in which guard 4 will be elevated, in order to give free access to the surface of table 2.

The upper end 49 of pawl 47 is normally in engagement with shoulder 53 of rod 15 and elevates said rod 15 when the toggle joint is returned to full line position illustrated in Fig. 2. Moreover, the upper end of pawl 47 has projecting therefrom in a lateral manner said pin 48 adapted to engage the lower surface of bar 56. The opposite end of bar 56 is pivoted at 57 to the upper end of auxiliary lever 41 and passes through the keeper 58 attached to the frame of the machine. Bar 56 carries a fixed adjustable cam 59. The lower surface of cam 59 is adapted to ride over the anti friction roller 60 supported on a pin 61 carried in bearings formed in keeper 58 and in the frame of the machine 1, whereby to elevate the free end of bar 56 that carries the adjustable block 62 in order to allow pawl 47

to move therewith after it has disengaged upper end 49 from shoulder 53.

Block 62 is held in place upon bar 56 by set screw 63. The lower surface of block 62 is beveled at 64, whereby to permit said block to ride over pin 48 while traveling in the reverse direction towards set position as shown in full lines in Fig. 2 and to prevent its passage in the other, unless elevated clear of pin 61 as shown in dotted lines in said Fig. 2.

In order to break the fall of guard 4 when descending, a piston rod 70 is attached to each of the members 13, 13 by projecting up through apertures therein. Lock nuts 74 are used to hold rods 70 in adjusted position. The lower end of each piston rod 70 carries a piston 70^a that plays in a cylinder 71 attached to the horizontal part 72 of bracket 17. Moreover, each of the cylinders 71 is equipped at its lower part with a pet cock 73, whereby to regulate the air pressure within the cylinder 71 and below the piston, in order to control the velocity with which said guard 4 descends.

The mechanism for operating guard 4 is the same on each end of machine 1. The parts are connected, however, whereby to act simultaneously by rock shaft 37 carried in bearings 65, 65 attached to the frame of machine 1. Rock shaft 37 has fixed at either end thereof to turn therewith levers 35, 35.

In order to connect the aforesaid mechanism for operating guard 4 to the power controlling means of the machine 1, link 38, as stated above, is pivoted to longitudinal movable rod 39. One end of rod 39 has an elongated aperture 66 for the projection therethrough of headed bolt 67 that is mounted to the frame of the machine and supports a friction stop member 67^a held normally against rod 39 by coiled spring 67^b mounted on bolt 67. The opposite end of rod 39 is pivoted at 68 to master lever 69 which is secured upon and mounted to turn idler shaft 80. Idler shaft 80 of well known construction is connected to shaft 81 by link 82 and arm 83 extending from a collar 84 fixed to turn with shaft 81. Shaft 81 is connected by a link to a clutch mounted on the power shaft, whereby the rocking of shaft 81 will actuate the clutch to control the operation of the machine. The last named parts are not shown for the reason that they are well known, as shown in patent to Bredenberg, issued May 22, 1906, No. 821,079. Therefore, the actuation of master lever 69 will rock also shaft 81 and as just described control the clutch for operating the machine.

A clutch 90 having a novel arm 91^a adapted to extend into the path of mutilated cam 92 is mounted to slide longitudinally upon shaft 80. Clutch 90 is held in mesh

with its counter part 93 by a coiled spring 94 surrounding shaft 80 and bearing at one end against clutch 90 and at the other against collar 95. Counter part 93 is adapted to turn with shaft 80. A link 96 is pivotally attached to clutch 90 at one end and to one end of bell crank lever 97 at the other. Bell crank lever 97 is fulcrumed at 98 to a bracket 99 attached to machine 1. Its free end lies under the shank 100 of foot pedal 101 that is fulcrumed at 102 to machine 1. Therefore, by pressing on pedal 101, lever 97 will be rocked to draw clutch 90 away from its counter part 93 and against the tension of coiled spring 94, whereby to permit the free operation of machine 1. Cam 92 is mounted to rotate upon shaft 105 and is equipped with a shoulder 106 adapted to engage arm 91^a of clutch 90, when said clutch 90 is in mesh with its counter part 93, whereby to stop the operation of the machine after one revolution of shaft 105. However, if pedal 101 is kept depressed, clutch 90 will be withdrawn from its counter part 93 and arm 91^a of said clutch 90 will be clear of cam 92, thereby allowing the free operation of machine 1 until pedal 101 is released again.

The operation of the machine is as follows: The operator first spreads the leather 110 to be pressed over the upper surface of vertically movable table 2 and after smoothing out any wrinkles grasps handle 11 of master lever 69 and pulls the same towards the dotted line position illustrated in Fig. 2. During the first part of this movement, lever 69 will effect an actuation of bar 39, link 38, lever 35, on one side of machine 1, rock shaft 37, lever 35 on the other side, and likewise links 40, 40, auxiliary levers 41, 41, bars 56, 56, whereupon, adjustable blocks 62, 62 will abut against pins 48, 48 attached to bell crank arms 47, 47 and push the upper ends 49, 49 of said arms free from shoulders 53, 53 formed in vertically movable arms 15, 15, whereby to allow guard 4 to descend. Arms 47 will be rocked to break the toggle joints and, thereafter, ultimately come to rest with pins 48 thereof resting on the upper edges of links 46, 46, by coiled springs 50, as shown in dotted lines in Fig. 2. Moreover, guard 4 will descend under proper restraint as controlled by the pistons in cylinders 71, 71.

During this movement, levers 35, 35 will actuate also horizontally movable bars 30, 30 which will slide under the lower edges 25, 25 of pawls 21, 21 until shoulders 26 of bars 30 are reached at which point, master lever 69 will be unable to move further, to throw in the clutch and start the operation of the machine unless guard 4 has descended to its full or covering position to prevent the insertion of a hand between table 2 and presser overhead 3. As guard 4 reaches its

lower or covering position, pins 20, 20 carried by vertically movable rods 15, 15 will strike the free ends of pawls 21, 21 and rock edges 25 thereof clear of shoulders 26 on bars 30. Thereafter master lever 69 can be pulled to its limiting position, whereby to continue the rocking of shafts 80 and 31 to throw in the clutch not shown that connects the power or clutch shaft also not shown of the machine with the operating parts, not shown, whereby to cause table 2 to move upward to press leather 110. Should the operator desire to permit table 2 to move upward several times without interruption, he will press pedal 101 in order to withdraw arm 91^a of clutch 90 clear of cam 92, thus permitting machine 1 to operate until pedal 101 is released again.

Immediately pedal 101 is released, clutch 90 will go forward under pressure of coiled spring 94 and mesh with its counter part 93. Arm 91^a of clutch 90 will be, thereafter, in the path of rotary cam 92, whereby the striking of shoulder 106 of cam 92 against arm 91^a will rock automatically shaft 80, and, through link 82 and arm 83, shaft 81 and clutch, not shown to inoperative position. The guard mechanism being connected to master lever 69 by movable rod 39 will return automatically to full line position illustrated in Fig. 2, when said master lever 69 returns.

It will be observed that should the operator have his hands between the upper surface of table 2 and overhead 3 when lever 69 is actuated, guard 4 would be unable to descend to cause pins 20, carried by rods 15, to release pawls 21 and, thereby arrest the further movement of lever 69 to operative position. Should the operator get his hand caught between the upper surface of table 2, descending guard 4, the sides 5, being made of heavy card board or stiff fabric will yield sufficiently to permit the operator to withdraw his hand.

Having thus described our invention what we claim as new and desire to secure by Letters Patent is:

1. In a guard for leather pressing machines having pressing surfaces, and power controlling means, a member for enclosing the pressing surfaces, vertically movable rods attached to said member, means for permitting said member to fall and means for raising said member, whereby to move said member from operative to inoperative position, and air compressing means for controlling the descending motion of said member.

2. In a guard for leather pressing machines having pressing surfaces and power controlling means, a member adapted to enclose said pressing surfaces, vertically movable rods attached to said member, automatic means for permitting the lowering

of said member to enclose said pressing surfaces, before said surfaces come together, pistons for controlling the velocity of descent of said member, and lever means for automatically raising said member to inoperative position.

3. In a guard for leather pressing machines having pressing surfaces and power controlling means, a member adapted to enclose said pressing surfaces, vertically movable rods connected with said member, toggle means for holding said rods in elevated position, means for permitting the breaking of said toggle means, whereby to lower said member to operative position, and pins carried by said vertically movable rods, whereby to release the operative mechanism of the machine.

4. In a guard for leather pressing machines having pressing surfaces and power controlling means, a member adapted to enclose said pressing surfaces, vertically movable rods connected intermediately with said member, toggle joints for holding said rods in elevated position, means for permitting the breaking of said toggle joints, whereby to lower said member to operative position, and automatic means for making said toggle joints, whereby to elevate said member.

5. In a guard for leather pressing machines having pressing surfaces and power controlling means, a guard member adapted to enclose said pressing surfaces, means for automatically permitting the lowering of said guard member under force of gravity before the operation of the machine, and pistons for controlling the rate of descent of said guard member.

6. In a guard for leather pressing machines having pressing surfaces and power controlling means, a guard adapted to enclose said pressing surfaces, means for automatically permitting the lowering of said guard under force of gravity, and air compression means for governing the velocity of descent of said guard.

7. In a guard for leather pressing machines having pressing surfaces and power controlling means, a guard for enclosing said pressing surfaces, means attached to said power controlling means for permitting the actuation of said guard under force of gravity to closed position, pistons intermediately connected with said guard, and cylinders for the reception of said pistons, whereby to control the movement of said guard.

8. In a guard for leather pressing machines having pressing surfaces and power controlling means, a guard for enclosing said pressing surfaces, rods adapted to travel with said guard, means connecting said guard with the power controlling means, whereby to permit the automatic actuation of said guard, pins carried by said rods, and pawls actuated by said pins, whereby to release the power controlling means to operate the machine.

9. In a guard for leather pressing machines having pressing surfaces and power controlling means, a guard comprising four side members adapted to enclose the pressing surfaces, rods attached to move with said guard, means for permitting the actuation of said guard connected with the power controlling means, other means carried by said rods, and pawls actuated by said last named means whereby to release the power controlling means to operate the machine.

10. In a guard for leather pressing machines having pressing surfaces and power controlling means, a guard, rods attached to move with said guard, levers connected with the power controlling means, whereby to permit the actuation of the rods and guard in an automatic manner, and a clutch for allowing the power controlling means to operate the machine continuously, while the guard is in closed position.

In testimony whereof we have affixed our signatures.

JOHN W. HERKEL.
JAMES D. McCOY.
